ELECTRICAL JUNCTION BOX

Nat Greene, Los Angeles, Calif., assignor to American Concrete Products Co., Los Angeles, Calif., a corporation of California

Filed Mar. 4, 1968, Ser. No. 10,830

Term of patent 14 years

Int. Cl. D13—03

U.S. Cl. D26—5

FIGURE 1 is an exploded, perspective view of an electrical junction box embodying my new design, a portion of an associated sealing ring being broken away;

FIGURE 2 is a front elevational view of the junction box of FIGURE 1, as assembled;

FIGURE 3 is a rear elevational view of the junction box of FIGURE 1, as assembled, with a portion being broken away;

FIGURE 4 is a top plan view of the assembled junction box; and

FIGURE 5 is a side elevational view of the junction box of FIGURE 2, with a portion of the cover thereof broken away.

I claim:

The ornamental design for an electrical junction box, as shown and described.
